UNITED STATES PATENT OFFICE.

JOHN GEORGE HEMMETER, OF PHILADELPHIA, PENNSYLVANIA.

CARD-HOLDER FOR JACQUARD LOOMS.

1,288,410.

Specification of Letters Patent. Patented Dec. 17, 1918.

Application filed January 23, 1918. Serial No. 213,394.

To all whom it may concern:

Be it known that I, JOHN GEORGE HEMMETER, a citizen of the United States, residing at 522 W. Indiana avenue, Philadelphia, in the county of Philadelphia and State of Pennsylvania, have invented new and useful Improvements in Card-Holders for Jacquard Looms, of which the following is a specification.

10 The invention relates to Jacquard looms and has for an object to provide a card holder therefor.

15 The invention comprehends among other features, the provision of a device for use in connection with the cylinder of a Jacquard loom, on which the usual cards are arranged, and which will serve as a stop to arrest and retain the cylinder in successive card-presenting positions, and particularly aid in 20 holding the cards in position on the cylinder to prevent them from slipping or sliding out of their proper position thereon.

I am aware that various forms of card-holding devices have been used heretofore, 25 and that the usual method is to employ a leather strap, which, bearing against the uppermost card on the cylinder, tends to hold the same firmly thereon. The straps, however, are subject to wear, and also mutilate 30 the cards, thus causing the loss of valuable time until the damage can be repaired. My device comprehends a simple arrangement that will not mutilate or harm the cards, and which will effectively perform 35 the function for which it is designed.

In the further disclosure of the invention, reference is to be had to the accompanying drawing, constituting a part of this specification, in which similar characters of reference denote corresponding parts 40 throughout all the views, and in which—

Figure 1 is an end elevation of the cylinder of a Jacquard loom in operating position to secure the card upon the cylinder.

45 Fig. 2 is a vertical sectional view taken substantially on the line 2—2 of Fig. 3, showing the manner in which the device operates to prevent slippage of the card.

Fig. 3 is a plan view of the structure 50 shown in Fig 1.

Fig. 4 is a fragmentary elevation of a modified form of my invention, and

Fig. 5 is an end view of the structure shown in Fig. 4.

55 Referring more particularly to the views, the numeral 10 indicates that part of a

Jacquard loom which may be termed the needle board, and figure 11 the usual cylinder journaled on suitable horizontal brackets 12. The cylinder 11 may be four or six-sided, 60 depending upon the character of the work, and the usual perforated design cards 13 are mounted, as shown, upon the cylinder, the cards being connected by suitable cords 14 or the like, as will be readily understood by 65 any one versed in the art of Jacquard looms. Pins 15 project from the cylinder and pass through openings 16 in the cards to aid in supporting the cards upon the faces of the cylinder, so that the cards will neatly fit 70 thereon as the cylinder is revolved.

A plurality of brackets 17 are secured upon the needle board, and journaled on said brackets is a horizontal rod 18 disposed immediately above the needle board, the rod 75 18 having suitably secured thereto a plurality of horizontally disposed fingers 19 which extend forwardly over the cylinder to rest upon the uppermost card on the upper face of the cylinder, with free ends of 80 said fingers being slightly turned out as at 20. A suitable coil spring 21 encircles the rod 18 adjacent an end thereof, and has one end bearing against one of the fingers 19, and the other end secured in one of the 85 brackets 17, said spring exerting a torsion on the rod 18, so as to hold the fingers 19 against the upper face of the uppermost card 13, as shown in Fig. 3. It will be understood that by winding the spring around 90 the rod a number of times, and then having the free end thereof bear against one of the fingers, the torsional effect of the rod 18 can be increased as desired.

With this construction it will be seen that 95 the fingers bearing down against the uppermost card, will hold the cylinder in its proper stationary position until it is turned to bring the next card in position, and referring to Fig. 2 it will be seen that in the moment of turning the cylinder, whereas, ordinarily the cards tend to jump up or slip off of the face of the cylinder upon which they rest, that with the provision of the pins 15, the said fingers will not only bear against 100 105 the card that is being moved out of uppermost position, but will immediately grip the edge of the card which is being moved into uppermost position, thus preventing slippage of the card coming into the uppermost 110 position, and serving to hold the card against the face of the cylinder.

In Figs. 4 and 5 I disclose a modified form of my invention and in which the spring is indicated by the numeral 21^a, and has one end thereof passed through a suitable opening 21^b in the rod 18, the other end of the spring being secured in an element 22 mounted to turn loosely on an end of the rod 18 and which element is shaped so that it can be readily gripped, the element being 5 in the nature of a tensioning device, so that after the spring has been mounted as mentioned, the element can be turned to increase the tension of the spring, and then a pin 10 23 passed through an opening 24 in one of the brackets 17, and one of a plurality of 15 openings 25 in the element 22 will serve to hold the element 22 in rigid and locked position on the rod 18. With this construction it will be seen that the torsional effect of the 20 spring 21 on the rod 18, can be increased or decreased as desired, and it will be clear that this will be of great advantage not only in mounting a device of the character described on a Jacquard loom, but also in the 25 continued use of a device of this character where the spring might get weak and will

either have to be renewed or tightened up in order to insure proper and accurate results.

It will be seen that I do not limit myself to the particular construction set forth 30 herein; that various slight changes may be made from the form of device illustrated, without departing from the spirit of the invention, the scope of which is defined in the appended claim. 35

I claim—

In a card holder for Jacquard looms, the combination with the cylinder and the frame of the loom with brackets on the frame, a rod journaled on the brackets, fingers projecting from the rod to extend over and above the cylinder and repose upon a card thereon, and a spring encircling the rod with one end of the spring connected to one of the brackets and the other end of the 45 spring connected to one of the fingers, whereby said spring will exert a torsional strain on the rod and hold the fingers against the face of the card.

In testimony whereof I affix my signature. 50

JOHN GEORGE HEMMETER.
